UNITED STATES PATENT OFFICE.

CHARLES F. SPARKS, OF ALTON, ILLINOIS.

BAG-FILLING MACHINE.

1,348,592.

Specification of Letters Patent.

Patented Aug. 3, 1920.

Application filed October 24, 1919. Serial No. 332,963.

To all whom it may concern:

Be it known that I, CHARLES F. SPARKS, a citizen of the United States, residing at Alton, Illinois, have invented a certain new and useful Improvement in Bag-Filling Machines, of which the following is a full, clear, and exact description, such as will enable others skilled in the art to which it appertains to make and use the same, reference being had to the accompanying drawings, forming part of this specification.

My invention relates generally to bag filling machines and more particularly to means for supporting the bag while it is being filled and handling said bag and removing it from the filling machine immediately after the filling operation has been accomplished.

In practically all the automatic bag filling machines now in general use, the bag or container to be filled is placed on a platform with the mouth of the bag around the lower end of the filling spout of the machine and the platform is then raised so as to position the bottom of the bag a few inches below the lower end of the discharge spout. As the filling operation takes place, the worm or feed screw operating within the discharge spout forces the material into the bag, and the latter and the platform supporting the same are forced downward until the bag is filled. When the bag carrying platform reaches a certain point in its downward travel, the operation of the feeding mechanism is discontinued and the filled bag is

now removed from the platform either by manual action of the operator or by mechanically operated means which drags the bag off the platform onto a weighing scale or onto an endless carrier. This procedure has certain disadvantages for, if the filled bags are relatively heavy, the removing operation involves a certain amount of time and considerable effort on the part of the operator; or, if the sacks are comparatively light in weight the removing operation must necessarily be unusually rapid in order to maintain the proper output of packed material.

In the best known automatic packing machines now in general use, the operator must be constantly on the alert and just at the proper time when the platform has moved downward a certain distance, and the feeding mechanism has been stopped, the friction brake must be released to permit the platform to move downward a short distance

further in order to permit the power actuated arm to swing around and remove the filled package. These operations consume a certain amount of time and, as stated, require the constant attention of the operator, and it is the principal object of my invention to generally improve upon the types of bag holding platforms and handling means now in general use and provide a platform that will automatically drop the filled bag onto a conveyer or the like so that said bag may be quickly removed without requiring any handling on the part of the operator.

Further objects of my invention are, to provide a construction which can be utilized in connection with practically all forms of bag filling machines now in general use and which construction is automatic in operation and very effective in the rapid handling of filled bags and effecting their removal from the filling machine.

With the foregoing and other objects in view, my invention consists in certain novel features of construction and arrangement of parts, hereinafter more fully described and claimed, and illustrated in the accompanying drawings, in which—

Figure 1 is a front elevational view of a portion of a bag filling machine and showing my improved bag handling mechanism associated therewith.

Fig. 2 is an elevational view of the bag handling mechanism with parts thereof in section.

Fig. 3 is a vertical section taken approximately on the line 3—3 of Fig. 1.

Fig. 4 is a horizontal section taken approximately on the line 4—4 of Fig. 1.

Fig. 5 is a horizontal section taken approximately on the line 5—5 of Fig. 1.

Referring by numerals to the accompanying drawings, 1 designates a horizontally disposed framework that is secured to and projects outwardly from a pair of substantially parallel uprights 2 and supported by said framework and between and in front of said uprights is a hopper 3 from which depends a discharge spout 4. Extending downward through this spout 4 is a vertically disposed shaft 5 and carried thereby and positioned immediately above the lower end of the spout 4 is a feed screw 5^a. While in operation this feed screw forces the granular or pulverized material downwardly through the feed spout but when at rest said

screw acts as a gate to prevent the downward passage of the material through the spout.

A vertically movable frame comprising 5 upright side members 6, a transverse top member 7, and a transverse bottom member 8 is arranged for sliding movement upon the uprights 2 and the weight of this sliding frame and parts carried thereby is counterbalanced by a weight or weights 9 which latter are carried by the lower ends of flexible members 10 such as chains or cables. These flexible members pass over a drum 11 that is journaled in suitable bearings on 10 the uprights 2 and from said drum the flexible members pass downwardly beneath pulleys 12 that are secured to the upright transverse member 7.

The bag supporting platform contemplated by my invention is preferably formed 20 in two parts, each preferably formed in a single piece and comprising a flat bottom member 13 and a substantially upright member 14. The upright members 14 occupy positions at angles of approximately one hundred twenty degrees with respect to the bottom members 13 and the upper ends of said upright members 14 are hinged upon horizontally disposed pins 15 that are seated 25 in and project forwardly from the upright side members 6 of the vertically moving frame. The bottom members 13 of the sectional platform extend forwardly from the upright members 14 and when in closed position or swung together, they coöperate to 30 form a substantially flat platform which receives and holds the bag in upright position while it is being filled. (See Figs. 1 and 2.)

Projecting outwardly from the upper 40 portions of the upright members 14 are short arms 16 in the outer ends of which are journaled rollers 17 and the latter being adapted to engage against the outwardly turned lower ends 18 of plates 19 that are secured 45 to and project forwardly from the uprights 2. The parts just described are effective in swinging the members forming the bag supporting platform into closed position during their upward travel and after the filled bag 50 has been discharged.

To retain the parts of the platform in closed position while supporting a bag, a hook-shaped detent 20 is utilized, said detent depending from a shaft 21 which latter 55 is journaled in suitable bearings on the under side of the lower transverse member 8 of the sliding frame. Projecting rearwardly from one end of the shaft 21 is a curved finger 22 and fixed to the rear portion of the 60 adjacent upright 2 are brackets 23 and 24, the same being spaced a suitable distance apart and with which the curved finger 22 is adapted to engage. The weight of the curved finger 22 practically counterbalances 65 the weight of detent 20 so that shaft 21

which carries the parts 20 and 22 will not tend to rock as a result of being overbalanced when finger 22 is out of engagement with brackets 23 and 24. Arranged for operation around a drum 25 that is journaled in suitable bearings is an endless conveyer 26, the same passing between the lower portion of the uprights 2 and secured to the uprights immediately above this endless carrier is a curved shield or supporting plate 27 75 that is adapted to act as a supporting wall for the filled bag when the latter drops onto the overrunning portion of the endless conveyer 80 and immediately below the supporting wall or shield is a transversely disposed plate or platform 28 that is adapted to serve as a support for the upper portion of the conveyer when the filled bag drops thereonto. 85

The operation of my improved bag handling machine is as follows:

At the beginning of the filling operations, an empty bag such as A is positioned around the lower portion of the spout 4, said bag resting upon the lower portion 13 of the two part platform, said parts being retained in closed position by the detent 20. As shaft 5 is rotated, screw 5^a forces the pulverized material into the lower portion of the bag and 90 as a result of the pressure of the feed screw 5^a upon the material packed into the bag, the latter and the platform supporting the same and the sliding framework which carries said platform will be forced downward 100 and such action will necessarily elevate the counterbalancing weights 9. When the downwardly moving parts have reached a certain point in their downward travel or when the bag is nearly full the finger 22 on 105 the end of shaft 21 that carries the detent will strike against the lower bracket 24 and be shifted so as to withdraw the free end of the detent from its position beneath the rear portions of the horizontal members 13 of 110 the platform and following this action, the weight of the filled bag will force the two parts of the platform away from each other or to the positions as shown by dotted lines in Fig. 1, and this will permit the bag to 115 drop downward onto the overrunning portion of the endless conveyer 26, by means of which latter it will be transferred to a weighing scale. As the filled bag thus drops onto the conveyer, said bag will be prevented from falling sidewise in either direction or rearwardly by the shield member 27 and the force of the fall of the bag will be broken by the platform or plate 28 which is located a short distance below that portion 120 of the carrier onto which the bag drops. Immediately after the filled bag discharges from the platform, the operator places an empty bag upon the lower portion of the discharge spout 4 and upon movement of the 125 130

proper lever by the operator the sliding framework and parts carried thereby will ascend due to the descent of the counterbalancing weights 9. As the parts of the platform move upwardly, the rollers 17 will engage against the rounded lower ends of the plates 19, thereby moving the parts of the platform into closed position and just before the parts reach their upper limit of movement, the curved finger 22 on the end of shaft 21 will strike against the underside of bracket 23, thereby swinging the detent into position so that its free end engages beneath the rear inner corners of the plates 13 and thus the platform will be maintained in closed position when the bag is being filled.

If desired, the means for controlling the starting and stopping operations of the shaft 5 may be thrown into and out of action by parts of my improved bag handling machine. For instance, the lever or other device which controls the starting or driving means for the shaft 5 may be actuated so as to start said shaft when the sliding frame reaches its upper limit of travel and likewise said lever or control means may be actuated to stop the shaft when the sliding framework reaches its downward limit of movement.

In Figs. 1 and 2 I have shown a shaft control lever 29 extending upwardly alongside one of the uprights 2 and pivoted levers 30 connected to said lever 29, said pivoted levers being adapted to be alternately engaged by a finger 31 that projects from one of the upright members 6 of the sliding frame.

If there is any tendency of the filled bag to maintain its position upon either end of the members 13 while the same are swinging away from each other or into open position, stripper arms such as 32 may be secured to the lower transverse member 8 and project forwardly over the platform members adjacent to the lower end of spout 4 and which strippers will be effective in limiting the lateral movement of the filled sack in either direction while it is dropping off the platform.

A bag handling device of my improved construction is comparatively simple, can be easily and cheaply manufactured, is applicable for use in connection with practically all forms of bag filling machines now in general use, is entirely automatic in operation, and is very effective in rapidly performing its intended functions.

It will be readily understood that minor changes in the size, form and construction of the various parts of my improved bag handling device can be made and substituted for those herein shown and described, without departing from the spirit of my invention, the scope of which is set forth in the appended claims.

I claim:

1. The combination with a bag filling machine, having a discharge spout and a packing member arranged for operation therein, of a vertically movable framework 70 mounted for operation adjacent to the discharge spout of the filling machine, and a drop bottom bag receiving platform associated with said framework, which framework and platform are adapted to move 75 downward by the pressure of the packing member on the material packed into the bag.

2. The combination with a bag filling machine, having a discharge spout and a 80 packing member arranged for operation therein, of a vertically movable framework mounted for operation adjacent to the discharge spout of the filling machine, and a bag receiving platform comprising parts 85 hinged to said framework and arranged to swing outwardly at the termination of the downward movement of the framework and inwardly during its upward movement and which framework and platform are adapted 90 to be moved downward by the pressure of the packing member upon the material fed into the bag carried by said platform.

3. The combination with a bag filling machine, having a discharge spout and a 95 packing member arranged for operation therein, of a vertically movable framework mounted for operation adjacent to the discharge spout of the filling machine, and a sectional bag receiving platform, the parts 100 of which are adapted to coöperate to support a bag while being filled, said parts being adapted to move away from each other to permit the discharge of the filled bag, and which framework and platform are 105 adapted to be moved downward by the pressure of the packing member upon the material packed into the bag on said platform.

4. The combination with a bag filling machine, having a discharge spout and a 110 packing member arranged for operation therein, of a vertically movable framework mounted for operation adjacent to the discharge spout of the filling machine, a sectional bag receiving platform, the parts of 115 which are adapted to coöperate to support a bag while being filled, said parts being adapted to move away from each other to permit the discharge of the filled bag, and means for holding the parts of the bag receiving platform in bag holding position and which framework and platform are adapted to be moved downward by the pressure of the packing member upon the material packed into the bag on said platform. 120

5. The combination with a bag filling machine, having a discharge spout and a packing member arranged for operation therein, of a vertically movable member ar- 130

2
ranged for operation adjacent to the discharge spout of the filling machine, bag holding means on said vertically moving member, parts of which holding means are 5 movable to release the filled bag, which member and bag holding means are adapted to be moved downward by the pressure of the packing member upon the material packed into the bag, and an endless carrier 10 adapted to receive the filled bag when released from the holding means.

6. The combination with a bag filling machine, having a discharge spout and a packing member arranged for operation 15 therein, of a bag handling mechanism comprising a vertically movable member and a drop-bottom bag receiving platform associated therewith, which member and platform are adapted to be moved downward by 20 the pressure of the packing member upon the material packed into a supported bag.

7. The combination with a bag filling machine, having a discharge spout and a packing member arranged for operation 25 therein, of a vertically movable platform adapted to receive a bag and hold the same while it is being filled, parts of which platform are adapted to move away from each other to drop the bag when the same has 30 been filled, which platform is adapted to be moved downward by the pressure of the packing member upon the material packed into a supported bag, and movable means for receiving the filled bag after it drops 35 from the platform.

8. The combination with a bag filling machine, having a discharge spout and a

packing member arranged for operation therein, of a vertically movable platform adapted to retain a bag while the same is 40 being filled and to move downwardly by the pressure of the packing member upon the material being packed into a supported bag, parts of which platform are movable to release the bag when filled. 45

9. The combination with a bag filling machine, having a discharge spout and a packing member arranged for operation therein, of a vertically movable platform adapted to retain a bag while the same is 50 being filled and to move downwardly by the pressure of the packing member upon the material being packed into a supported bag, parts of which platform are movable to release the bag when filled, and means 55 for elevating said platform after the filled bag has been released.

10. The combination with a bag filling machine, having a discharge spout and a packing member arranged for operation 60 therein, of a vertically movable platform adapted to retain a bag while the same is being filled and to move downwardly by the pressure of the packing member upon the material being packed into a supported 65 bag, parts of which platform are movable to release the bag when filled, means for elevating said platform after the filled bag has been released, and means for shifting the movable parts of the platform into position to receive an unfilled bag. 70

In testimony whereof I hereunto affix my signature this 21st day of October, 1919.

CHARLES F. SPARKS.
